UNITED STATES PATENT OFFICE.

EDWARD A. JOHNSTON AND CHARLES I. LONGENECKER, OF CHICAGO, ILLINOIS,
ASSIGNORS, BY MESNE ASSIGNMENTS, TO INTERNATIONAL HARVESTER
CORPORATION, A CORPORATION OF NEW JERSEY.

CARBURETER.

1,150,202.

Specification of Letters Patent. Patented Aug. 17, 1915.

Application filed April 29, 1911. Serial No. 623,998.

To all whom it may concern:

Be it known that we, EDWARD A. JOHNSTON and CHARLES I. LONGENECKER, citizens of the United States, residing at Chicago, in 5 the county of Cook and State of Illinois, have invented certain new and useful Improvements in Carbureters for Internal-Combustion Engines, of which the following is a specification.

10 Our invention relates to carbureters that are used in connection with internal combustion engines, and is designed in particular for use in connection with either light or relatively heavier hydrocarbon oils of a 15 greater or less volatile nature as combustible elements, and consists in means for controlling the admission of either liquid separately, by both manually operable and automatic charge throttling mechanism, and also 20 means for admitting regulated quantities of water as a constituent element of the gaseous mixture, the object of our invention being to provide a mechanism simple in construction, readily adjusted to meet the varying conditions 25 to which this class of inventions is subjected, and efficient in operation. We attain these objects by means of the mechanism illustrated by the accompanying drawings, in which—

30 Figure 1 is an end elevation of part of an engine cylinder having our improved carbureter connected therewith; Fig. 2 is a longitudinal sectional view of part of the cylinder, and a vertical sectional view of 35 the carbureter mechanism; Fig. 3 is a top plan view of part of Fig. 2 along line A—B; Fig. 4 is a vertical sectional detail of part of Fig. 3 along line D—E; Fig. 5 is a cross section of part of Fig. 1 along line C—D; 40 Fig. 6 is a detached detail of part of the charge throttling mechanism; Fig. 7 is a detail of one of the throttling valves; Fig. 8 is a detail of part of the charge throttling mechanism; Fig. 9 is a vertical sectional 45 elevation of a gasolene float feed cup; and Fig. 10 is a side elevation of a gasolene supply receptacle attached to the air pipe forming part of the carbureter mechanism.

The same reference characters designate 50 like parts throughout the several views.

1 represents the cylinder of an internal combustion engine, 2 the head secured thereto, and 3 the water jacket space surrounding the cylinder.

4 represents a valve cage received by an 55 opening through the upper wall of the cylinder, the cage being secured to the cylinder by means of stud bolts 5.

6 represents an intake valve of the mushroom type, having its seat at the inner end 60 of the cage and provided with a stem 7 that is slidably received by a vertically arranged sleeve 8 integral with the cage and projecting beyond its upper wall.

9 represents a coiled compression spring 65 that in this instance surrounds the projecting end of the sleeve and the valve stem and operative between the wall of the cage and a pressure adjusting nut 10 at the upper end of the valve stem in a 70 well-known manner to control the movement of the valve.

The valve cage includes a laterally turned portion 11 at its outer end that is provided with a vertically arranged flange member 75 12, to which is secured the lower laterally turned end of a mixing chamber 13, that includes a vertically arranged portion 14. Surrounding the vertical portion 14 is an annular chamber 15, that is divided into 80 three separate receptacles by means of vertical partition walls 16, that are provided with laterally projecting shelf portions 17.

18 represents a vertically arranged air conduit having a flanged base 19 at its lower 85 end that forms a cover for the annular chamber 15 and is secured thereto by means of screws 20, that are received by threaded openings in the shelf portions of the partitions.

21 represents a common form of float feed cup, having a pipe connection 22 with one of the series of receptacles designated as 23, and 24 represents a pipe designed to connect the float feed cup with a source of gasolene 95 supply, including a small tank 24¹ that is preferably attached to an extension 25 of the air admission conduit.

26 represents a common form of needle valve designed to be operated manually for 100 the purpose of controlling the admission of gasolene to the mixing chamber from the receptacle 23.

27 represents a pipe having one end communicating with one of the receptacles designed to receive a quantity of heavy oil 105 when desired for the regular operation of the engine and designated by the reference

character 28, and the opposite end of the pipe may be connected with a pump mechanism (not shown), and operative to provide a continuous flow of oil to the receptacle 5 from any source of supply, and 29 represents an overflow pipe leading from the receptacle back to the source of oil supply, whereby a constant level of oil is maintained in the receptacle.

10 30 represents a needle valve like valve 26, and operative to control the admission of heavy oil to the carbureting chamber in a like manner.

The third receptacle of chamber 15 is 15 designated by reference character 31, and is designed to hold a quantity of water, the water being conducted from any preferred source of supply by means of a pipe 32, and 33 represents an overflow pipe leading from 20 the receptacle whereby a constant level of water is maintained therein. A needle valve 34, like valves 26 and 30, is operative to control the admission of water to the mixing chamber. The needle valves are all arranged 25 in the same horizontal plane, and the overflow pipe from the receptacle for water leads from a level below that of the level of the overflow pipe leading from the receptacle for heavy oil, as shown in Fig 4. The flow 30 of liquid from the several receptacles through the feed nozzles controlled by means of the manually operative needle valves is provided for by means of vertically arranged conduits leading from the nozzles 35 toward the bottom of the receptacles, as designated by reference character *a* on Figs. 2 and 5 of the drawing.

35 represents a common form of butterfly valve having a centrally arranged stem 36 40 that is pivotally mounted in opposite walls of the air conduit 18, and provided at one end with a lever arm 37; the valve being operative to control the admission of air to the carbureting chamber. 38 represents a 45 valve of the same type, having a stem 39 pivotally mounted in opposite walls of the laterally arranged portion 11 of valve cage 4, and having oppositely disposed lever arms 40 secured to one end thereof.

50 41 represents a connecting rod having its opposite ends pivotally connected with arm 37 and one of the arms 40, the rod including a threaded portion 42 that is adjustably received by a sleeve portion 43 forming part 55 of a connecting yoke 44. The valve 38 is operative to throttle the passage for combustible mixture leading from the carbureting chamber to the intake valve, and 45 represents a link having one end pivotally connected with the other arm 40, and the opposite end of the link may be connected with a governor mechanism forming part of the equipment of the engine.

60 In the operation of our invention, when 65 starting the engine with the combustion and

carbureting chamber cold, it is desirable to use a light hydrocarbon, such as gasoline, for a limited time until the chambers become sufficiently heated by the burned gases to properly vaporize the heavier oils, such as 70 kerosene or crude petroleum, and for that purpose gasoline is allowed to flow from the tank 24 through the float feed cup 21 to the gasoline receptacle 23, from which it is drawn by the suction stroke of the engine 75 in a common way through the nozzle of the hand controlled needle valve mechanism, the feed nozzle of the latter being raised slightly above the level of the fluid in the receptacle. When the combustion and carbureting chambers have become heated sufficient to vaporize the heavier oil the needle valve controlling the supply of gasoline is closed and the one controlling the admission of heavier oil 80 opened, and as it is desirable that water be admitted to form a part of the combustible mixture when kerosene or crude oil is used, for the purpose of preventing preignition under high compression of the charge, a regulated quantity is admitted by opening 85 the needle valve more or less that controls 90 its admission.

The speed of the engine is governed by means of the throttling valve 38 closing more or less of the passage leading from the carbureting chamber to the intake valve in a manner to regulate the volume of combustible mixture drawn into the cylinder during the suction stroke of the engine. The mixture throttling valve and the valve 95 controlling the admission of air to the carbureting chamber being connected with each other in a manner to move in unison, both are controlled by the engine governor, and the degree of vacuum in the carbureting chamber depends upon the movement of the air throttling valve, the movement thereof being controlled by the load upon the engine, and consequent degree of vacuum in the cylinder as the charge is drawn through 100 the port controlled by the intake valve. When the engine is running under full load and a maximum amount of fuel is required, it is desirable that more water be admitted to the carbureting chamber, and as the load 105 is reduced within certain limits the supply of water is gradually reduced in proportion to the fuel admitted and both are controlled by the degree of vacuum in the carbureting chamber. When the engine is under a comparatively light, or no load, it is desirable that little or no water be admitted, as the mixture would otherwise become too much saturated with moisture, and with less heat from the burned gases the cylinder temperature is lowered, the result being that the mixture is not readily ignited. As a remedy for such inefficiency we have placed the level 110 of water in the receptacle below that of the oil in its receptacle, and by keeping the two 115

feed nozzles at the same level the degree of vacuum in the carbureting chamber is not sufficient to draw water from its feed nozzle when the engine is running under lighter load conditions.

What we claim as our invention, and desire to secure by Letters Patent, is:

1. A carbureter for internal combustion engines including, in combination, a carbureting chamber, a mixture conduit leading from said chamber, an air conduit leading into said chamber, a series of three receptacles surrounding said chamber and having manually operative valves controlling a communication between said receptacles and said chamber, said receptacles communicating, respectively, with sources of gasolene or other light hydrocarbon, heavy hydrocarbon and water supplies, and valves operating simultaneously to control the degree of vacuum in said chamber and thereby the quantity of fuel and water drawn from said receptacles, the level of water in relation to the feed valve therefor being such that no water is admitted when the load upon the engine falls below a predetermined limit, said valves also operating in a manner to control the flow of mixture from said chamber, one of said valves being located in advance of said manually controlled valves.

2. A carbureter for internal combustion engines having, in combination, a carbureting chamber, a mixture conduit leading from said chamber, an air conduit leading into said chamber, a series of three receptacles surrounding said chamber and communicating, respectively, with sources of gasolene or other light hydrocarbon, heavy hydrocarbon and water supplies, manually operative valves controlling the communication between said receptacles and said chamber, respectively, the level of water in said water receptacle in relation to the feed valve therefor being such that no water is admitted when the load upon the engine falls below a predetermined limit, a mixture throttling valve pivotally mounted in the walls of said mixture conduit, an air throttling vacuum controlling valve pivotally mounted in said air conduit in advance of said manually operative valves, and means for operating said valves simultaneously, said means including lever arms secured to said valves, and a connecting rod longitudinally adjustable as to length and having the opposite

ends thereof pivotally connected with said lever arms.

3. A carbureter for internal combustion engines including, in combination, a carbureting chamber, a mixture conduit leading from said chamber, an air conduit leading into said chamber, means for controlling the degree of vacuum in said carbureting chamber, an annular chamber surrounding said carbureting chamber and having radially arranged partitions therein that divide said annular chamber into three separate receptacles for the reception of gasolene or other light hydrocarbon, heavy hydrocarbon and water, respectively, manually operative valves controlling the communication between said receptacles and said carbureting chamber, respectively, and having the feed nozzles thereof projecting into said carbureting chamber and concentrically arranged in the same horizontal plane and operative to control a flow of liquid from said receptacles to said carbureting chamber, and means for controlling the level of fluid in said receptacles, the level of water being maintained in a lower plane than that of the heavy hydrocarbon in relation to their respective controlling feed valves, whereby no water is admitted when the load upon the engine falls below a predetermined level.

4. A carbureter for internal combustion engines including, in combination, a carbureting chamber, an air conduit leading to and a mixture conduit leading from said chamber, three receptacles around said chamber having controlled communication therewith, said receptacle communicating, respectively, with sources of light hydrocarbon, heavy hydrocarbon and water supplies, and valves operating simultaneously to control the degree of vacuum in said chamber and thereby the quantity of hydrocarbon and water drawn from said receptacles, the water control being such that no water is admitted to said chamber when the engine load is below a predetermined limit, said valves also operating to control the flow of mixture from said chamber.
